APPARATUS FOR CONTROLLING DISCHARGE LAMPS

Original Filed June 7, 1933

UNITED STATES PATENT OFFICE

1,986,614

APPARATUS FOR CONTROLLING DISCHARGE LAMPS

Willem F. Westendorp, Schenectady, N. Y., assignor to General Electric Company, a corporation of New York

Application June 7, 1933, Serial No. 674,698
Renewed September 18, 1934

8 Claims. (Cl. 176—124)

My invention relates to apparatus for controlling electric discharge lamps operated on polyphase alternating current circuits. It relates particularly to apparatus for varying the illumination of discharge lamps having the form of long, narrow tubes, sometimes termed positive column lamps, which because of the large ratio of their length to their diameter will not start operating merely with the application of a voltage which is sufficiently high to keep them operating after they have been started. Where such lamps are operated by alternating current it is necessary to restart them at each half cycle upon which they operate.

One object of my invention is the provision of improved apparatus for starting electric discharge lamps operated on polyphase circuits. Another object is the provision of improved apparatus for varying at will the amount of illumination produced by such lamps when operated on polyphase circuits.

My invention will be better understood from the following description taken in connection with the accompanying drawing, and its scope will be pointed out in the appended claims.

Referring to the drawing, Fig. 1 is a circuit diagram illustrating one embodiment of my invention; and Fig. 2 shows a series of curves to illustrate the operation of the apparatus shown in Fig. 1.

In Fig. 1, reference number 5 represents a polyphase alternating current source of supply, which for example may be 120-volt, 60-cycle, and which in the present case is shown as three phase, the phase conductors thereof being represented by the letters A, B, and C. Connected between the respective phase conductors and neutral, which is represented by the letter N, are the three similar electric discharge lamps 6, 7, and 8, whereby each lamp is operated on a separate phase of the alternating current supply. The lamps are of the positive column type each comprising a tubular envelope of transparent material such as glass or quartz, having a cathode 9, which may be a "hot" or a "cold" cathode but preferably is a hot cathode, in an enlargement or bulb at the lower end of the lamp and an anode 10 at the opposite end. The cathode 9, if a "hot" cathode, may be provided with a heater of well-known form which is not shown, nor is the heating circuit thereof shown. An example of a "cold" cathode is the well-known mercury cathode. Depending upon the character of the light desired from the lamp, the envelope after having been evacuated is

supplied with a metal vapor such as sodium vapor or mercury vapor or with a gas such as neon, krypton, etc., or with a mixture of a gas and a vapor, all being under low pressure. Inasmuch as a lamp of this character has a negative volt-ampere characteristic a suitable impedance must be used in circuit with the lamp to hold the current taken thereby within safe limits. For this purpose I have shown the reactor 11 connected in series with the anode of each lamp. This reactor has in addition to the usual winding thereof the auxiliary winding 12 comprising a few turns of wire wound on the same core as the main winding and thereby comprising in effect a transformer whose purpose is to induce a voltage impulse in the main winding of the reactor to cause the lamp to start as will be explained later.

As mentioned above, a discharge lamp of the type illustrated will not start of its own accord merely by connecting it with the source of current supply 5, but if it is started in each positive half cycle, namely, the half cycle in which its anode is positive with respect to its cathode, it will continue to operate through the remainder of each of those half cycles. In order to start the lamp in each positive half cycle I cause a voltage impulse to be applied to the lamp in each of those half cycles, which impulse added to the voltage of the supply circuit is sufficient to start a discharge in the lamp. The means which I have devised for applying the voltage impulses for starting the lamp comprises the capacitor 14 arranged in series with the auxiliary winding 12 and connected through the rectifier 15 and controlling resistor 16 with a suitable source of voltage. Certain broad aspects of my invention for so starting discharge lamps are disclosed and claimed in my Patent No. 1,976,645, Oct. 9, 1934.

In accordance with my present invention the source of voltage for charging the capacitor 14 is the three phase step-up transformer 17 the primary of which is connected with the polyphase source 5 and which, for example, may be wound for 120 volts while the secondary may be wound for 1500 volts. The capacitor 14, associated with lamp 8 which is connected with phase C, is supplied with voltage through rectifier 15 not from phase C of transformer 17 but with reversed phase A of that transformer, the reversal of the phase being indicated by showing the neutral connection of the secondary at the opposite end from the neutral connection of the primary. The capacitor 14 thus charged from

reversed phase A of transformer 17 is allowed quickly to discharge at the proper instant through the auxiliary winding 12, the discharge circuit including the resistor 18 and the control device or valve 19. This device preferably is a vapor electric discharge device and is shown having an anode 20, a control grid 21 and a hot cathode 22. When device 19 begins to conduct current by the application of the proper voltage to its grid the relatively large discharge current from the capacitor passing through the winding 12 induces a voltage in the main reactor winding which is sufficient to cause the lamp to start. The instant at which the vapor device allows the capacitor to discharge through winding 12 is determined by the phase controlling apparatus now to be described.

This apparatus is shown as comprising a stator 25 having a three phase distributed winding which is connected with the polyphase source of supply 5. Inductively related with this winding is the rotor 26 which also has a three phase distributed winding, which is shown connected with a three phase load device 27 comprising the three resistors 28. These resistors are shown as Y-connected, the neutral being connected with the neutral N and the opposite ends of the resistors being connected through resistors 29 with the grid circuits of the vapor electric devices 19. Since the rotating magnetic field produced by the stator 25 induces a three phase voltage in the winding 26 of the rotor the voltages applied to the grids of the vapor devices 19 will be three phase and of the same frequency as that of the source 5, and will be similarly related to the anode voltages of said devices. By angularly adjusting the rotor with respect to the stator the phase of the voltage applied to the grid of each device 19 may be delayed or advanced with respect to the phase of the anode voltage thereof. Hence the instant of starting of the discharge lamps can be varied at will throughout the half cycle upon which they operate thereby causing the illumination produced to be varied accordingly. This change in illumination may be effected manually if desired, but I prefer to employ automatic means to cause it to vary uniformly and at regular intervals. For this purpose I have provided the rotor 26 with the shaft 50 upon which is mounted the crank 31 arranged to engage the cam 32. The torque produced between the rotor and stator is sufficient to hold the arm 31 in engagement with the cam. For driving the cam I have shown the clock 33 which in rotating the cam causes the rotor to oscillate slowly back and forth through the necessary angle to give the proper phase adjustment and thereby periodically to vary the illumination.

While I have described the above apparatus with special reference to that associated directly with lamp 8, which is operated on phase C, it is to be understood that a similar apparatus is associated with each of the other lamps 6 and 7, which are operated on phases A and B respectively, the only difference being that the charging circuit for the capacitor associated with lamp 7 is connected with reversed phase C, indicated by -C, and the charging circuit for the capacitor associated with lamp 6 is connected with reversed phase B indicated by -B.

To assist in the clear understanding of the operation of the above-described apparatus I have shown a series of waves in Fig. 2 representing the various phase relations existing in

the apparatus. Waves +A, +B, and +C represent the applied voltage waves of the polyphase source 5, which waves are displaced from one another 120 degrees. The dotted curve -A, which for convenience is drawn to a small scale, 5 represents the reversed A phase produced by a reversal of the secondary A phase winding of transformer 17. Curve 36 represents the voltage the capacitor 14 associated with lamp 8 during the charging of this capacitor from reversed phase A. Curve 37 represents the voltage applied to the grid of vapor device 19 associated with lamp 8 produced by the phase controlling apparatus. At the point where this grid voltage becomes positive the vapor device immediately 15 begins to conduct current and therefore to allow the capacitor suddenly to discharge through winding 12 and hence start lamp 8. The vertical line 38 represents the condenser discharge and also the instant at which the lamp begins 20 to operate. The lamp having thus been started continues to operate through the remainder of that half cycle, that part of the half cycle through which the lamp operates being indicated by the hatching. It will thus be seen that 25 by making use of the reversed A phase to charge the capacitor a full discharge is available at the instant at which the lamp is to be started. In a similar manner the capacitor associated with lamp 6, which is on phase A, is charged from reversed phase B and is discharged by the operation of the vapor device associated therewith. Also the capacitor associated with lamp 7, which is on phase B, is charged from reversed phase C and is discharged at the proper instant by the 30 vapor device associated therewith. As the rotor 26 of the phase controlling apparatus is adjusted to delay the grid voltage 37 of device 19, the instant at which the lamp 8 is started is correspondingly delayed in each positive half 40 cycle. Finally when the grid voltage 37 reaches a delayed position corresponding to that indicated by the dotted line 40 the operating voltage applied to the lamp has reached a value too low to maintain a discharge and hence the lamp 45 does not start. The capacitor, however, does discharge each time the vapor device is tripped and the impulse voltage produced in the reactor of the lamp produces a weak flash of light in the lamp. It will be noted however that when 50 the grid voltage has reached a still further delayed position than that represented by 40 where the lamp should be entirely dark the tripping of the vapor device occurs at the beginning of the next positive half cycle of reversed phase A. 55 The current which would charge the capacitor from reversed phase A now is free to pass through the vapor device and since the condenser receives only that small charge corresponding with the potential drop across resistor 18 60 and the vapor device no sudden discharge takes place; hence the lamp remains totally dark at those times at which illumination is not desired.

For convenience I have shown but one lamp connected with each phase. It will be understood, however, that a plurality of lamps may be employed if desired, the lamps in each phase preferably being connected in parallel. For convenience also I have not attempted to show the various waves in Fig. 2 in their true relative 70 proportions except as to frequency and phase.

I have chosen the particular embodiment described above as illustrative of my invention, and it will be apparent that various modifications may be made without departing from the spirit 75

and scope of my invention which modifications I aim to cover by the appended claims.

What I claim as new and desire to secure by Letters Patent of the United States is:

- 5 1. In combination, a source of polyphase alternating current supply, an electric discharge lamp connected to operate on one phase thereof, and means energized by another phase thereof for inducing a starting voltage in the circuit of said lamp.
- 10 2. In combination, a source of polyphase alternating current supply, an electric discharge lamp connected with one phase thereof, means for reversing another phase thereof, energy storing means connected therewith and means for causing the energy stored in the storing means to produce a starting voltage in said lamp.
- 15 3. In combination, a source of polyphase alternating current supply, an electric discharge lamp connected with one phase thereof, a reactor in said connection, means for reversing another phase of said supply, a capacitor arranged to be charged from said reversed phase and means for causing the energy stored in said capacitor to induce a starting voltage in said lamp.
- 20 4. In combination, a source of polyphase alternating current supply, an electric discharge lamp connected with one phase thereof, a reactor in said connection having an auxiliary winding, means for reversing another phase of said supply, a capacitor arranged to be charged from said reversed phase, means for discharging said capacitor through said auxiliary winding comprising a grid controlled vapor electric discharge device and phase controlling apparatus connected with the grid circuit of said device.
- 25 5. In combination, a source of polyphase alternating current supply, an electric discharge lamp connected with one phase thereof, means for reversing another phase thereof, means energized by said reversed phase for supplying a starting voltage to said lamp, and means for varying the point on the wave of said one phase at which said starting voltage is produced.
- 30 6. In combination, a source of polyphase alternating current supply, an electric discharge lamp connected with one phase thereof, a reactor in said connection, means for reversing another phase of said supply, a capacitor arranged to be charged from said reversed phase, means for causing the energy stored in said capacitor to induce a starting voltage in said lamp, and phase controlling apparatus for varying the point on the wave of said one phase at which said energy induces said starting voltage.
- 35 7. In combination, a source of polyphase alternating current supply, an electric discharge lamp connected with one phase thereof, a reactor in said connection having an auxiliary winding, means for reversing another phase of said supply, a capacitor arranged to be charged from said reversed phase, means for discharging said capacitor through said auxiliary winding comprising a grid controlled vapor electric discharge device and phase controlling apparatus connected with the grid circuit of said device.
- 40 8. In combination, a source of polyphase alternating current supply, an electric discharge lamp connected with each phase thereof, means for reversing each phase, a reactor in circuit with each lamp, a capacitor arranged to be charged from each reversed phase, means responsive to the discharge of each capacitor for inducing a starting voltage in the lamp connected with a different phase and phase adjusting apparatus for controlling the discharge of said capacitors.

CERTIFICATE OF CORRECTION

Patent No. 1,986,614.

January 1, 1935.

WILLEM F. WESTENDORP.

It is hereby certified that error appears in the printed specification of the above numbered patent requiring correction as follows: Page 2, second column, line 27, for "discharge" read charge; and that the said Letters Patent should be read with this correction therein that the same may conform to the record of the case in the Patent Office.

Signed and sealed this 12th day of March, A. D. 1935.

Leslie Frazer

Acting Commissioner of Patents.
